US00D869909S

(12) **United States Design Patent** (10) **Patent No.:** **US D869,909 S**
(45) **Date of Patent:** **** Dec. 17, 2019**

(54) **CONTAINER ENCLOSURE**

- (71) Applicant: **CAMCAL ENTERPRISES, LLC**,
Phoenix, AZ (US)
- (72) Inventors: **Matthew T. Campbell**, Cave Creek,
AZ (US); **Adam Callinan**, Manhattan
Beach, CA (US)
- (73) Assignee: **Camcal Enterprises, LLC**, Phoenix,
AZ (US)

(**) Term: **15 Years**

(21) Appl. No.: **29/688,748**

(22) Filed: **Apr. 24, 2019**

Related U.S. Application Data

- (63) Continuation of application No. 29/670,065, filed on
Nov. 13, 2018, now Pat. No. Des. 852,001.

CLAIM

The ornamental design for a container enclosure, as shown
and described.

DESCRIPTION

FIG. 1 is an isometric view of a front, top, and right side of
an ornamental design for a container enclosure;

FIG. 2 is a front elevational view of the container enclosure
of FIG. 1;

FIG. 3 is a rear elevational view of the container enclosure
of FIG. 1;

FIG. 4 is a right side elevational view of the container
enclosure of FIG. 1;

FIG. 5 is a left side elevational view of the container
enclosure of FIG. 1; and,

FIG. 6 is a top plan view of the container enclosure of FIG.
1.

The dash-dash-dash lines are for the purpose of illustrating
environmental structure and form no part of the claimed
design. The dash-dot-dash line forms no part of the claimed
design and represents a boundary line.

1 Claim, 4 Drawing Sheets
